UNITED STATES PATENT OFFICE.

WALTER T. MARGETTS, OF NEW YORK, N. Y., ASSIGNOR TO HARRY G. JENNISON, OF TOLEDO, OHIO.

PAVEMENT.

1,402,942.

Specification of Letters Patent. Patented Jan. 10, 1922.

Application filed March 7, 1917. Serial No. 152,984.

To all whom it may concern:

Be it known that I, WALTER T. MARGETTS, a citizen of the United States of America, residing at New York, New York County, 5 New York, have invented new and useful Pavements, of which the following is a specification.

This invention relates to paving.

This invention has utility in the production of pavement involving dissimilar materials as wood and stone or brick.

Referring to the drawings:

Fig. 1 is a perspective view showing the features of pavement production as to mode 15 of laying;

Fig. 2 is a fragmentary perspective view of the pavement completed by use, the pavement of Figs. 1 and 2 being especially adapted for the utilization of old paving 20 blocks as of granite or other stone;

Fig. 3 is a view similar to Fig. 1 with bricks as the inorganic or relatively frangible material to be alternated with the wood; and

Fig. 4 is a fragmentary perspective view 25 of the pavement of Fig. 3 when worn to completed condition.

In the production of pavements as herein disclosed, it is desirable to provide a 30 substantial foundation 1, say of concrete, adequate to carry the loads and having its surface determined as to the grade of the finished pavement. In the building on this base of a pavement embodying say old 35 granite paving blocks, it is desirable to spread over the concrete base, a moist mortar bed 2 of sand and cement, and dispose in parallel rows on this moist bed, the granite blocks 3 with the space 4 between 40 each row.

The setting of these blocks may be followed up by filling into the spaces 4 moist mortar 5 up to a grade say $3\frac{1}{2}$ " below the top of the granite block if a 4" deep wood 45 block 6 is to be used. This filling of moist mortar bed 5 of sand and cement is tamped well into the spaces 4 to determine the proper level.

The wood blocks 6 are set to break joints 50 with the granite blocks 3 and are set to have their grain up and further are provided with the expansible end take up or ribs 7, and placed into position in the spaces 4 above the moist mortar bed 5. The 55 blocks may be pushed down, say at the ini-

tial setting to about $\frac{1}{2}$ " exposed, then with a broad rammer be brought down to have their top level about $\frac{1}{2}$ " above the granite blocks. The incomplete paving surface provided by the granite blocks 3 is completed 60 by these alternating rows of wood paving blocks 6, say impregnated with creosote or properly rendered aseptic. However, to assist in bringing this paving surface to a self-finishing level, an asphaltic or tar filler 65 mixed hot with proportion of say one part of the asphalt or creosote to two parts of sand, is used as a topping or coating applied as the sheet 8 bringing the entire pavement to a level wear-off surface for the 70 traffic which forces this filler to occupy all interstices and gradually wear down to work a uniform level of pavement through the topping.

The interaction between the relatively 75 frangible inorganic blocks 3 and the relatively tough organic impregnated wood blocks 6 results in the inorganic blocks 3, say if from old road work and rounded, in working to a straight surface with the wood 80 blocks which wood blocks swell up or conform to the edges of the granite blocks in such a way as to protect such edges from fracture.

There is further utility in that these wood 85 blocks with grain up have their maximum expansion regions in the plane of the pavement thus assisting in gripping laterally to save the granite block edges, but further 90 co-operating longitudinally to a greater extent. The expansion of the wood blocks in the longer dimension direction is partially taken up by the crushable lugs 7. However, in the squeezing of the wood blocks by the more rigid earthen blocks, there results a 95 mutual interaction for distributing the load throughout the pavement.

This is a feature of utility in pavement life maintenance and is further evidenced as of great utility in its co-operation with 100 track work in the street. The rails are so squeezed as to be held against vibration. There is enough wood in the pavement as directly coating with the base for effectively deadening sound transmission. This 105 gripping effect with a desirable anti-skid pavement has even greater utility in the special work along the street railway lines holding the rails and switches at turns and cross-overs against the working loose due to 110

the severe traffic to which they are subjected thereby materially lengthening the life of such installations.

There may be in this gripping action for 5 distributing the load on the granite blocks and the wood blocks, a kind of arched action in the bind due to the snug expansion fitting say between the rails 9, 10.

The granite blocks, initially rounded if 10 second hand as shown in Fig. 1, in the automatic finishing of the pavement appear as the truly surfaced blocks 11, Fig. 2, brought to the surface of the wood paving blocks 6 which have their terminal lugs 7 more or 15 less compacted according to the crushing strain.

This great utility in the utilization of old paving stones as well as new is also present in the vitrified or clay product paving blocks 12 incorporated with the wood blocks 6 as shown in Fig. 3, the laying of which may occur in a similar manner as of the granite blocks 3 except that the paving base may not need any supplemental filling 25 in the spaces 4 or the pavement may be laid direct upon a uniform pavement base.

The wood strengthens and gives life to the brick for the weakness of the brick is not present. The wood of the block pre- 30 cludes any beating or breaking off of the brick block edges. The slippery features of the impregnated wood blocks do not develop as objectionable skidding qualities in the combined pavement because the stone or 35 brick anti-skid feature provides a surface

for ready adherence of heavy vehicle traffic as well as rapidly moving cars.

This pavement of dissimilar blocks, accordingly, is one of great load carrying strength, of practically permanent life in itself as it seals the base from moisture attacks, is sanitary in that it is readily and thoroughly cleaned even by flushing, and amalgamates as a unit for carrying the load and stiffening railway tracks. 45

What is claimed and it is desired to secure by Letters Patent is:

1. A pavement embodying a foundation, spaced rows of earthen blocks on said foundation, grain-up wood blocks disposed in said spaces to complete the pavement as to pavement extent, said wood blocks protruding above the earthen blocks, and a surfacing material over the earthen blocks adapted to be worn down by traffic as the 50 protruding portions of the wood blocks are worked into protecting position for the edges of the earthen blocks.

2. The method of completing a pavement embodying installing an uneven surface 60 grain up wood block and earthen block pavement, with the wood blocks protruding above the earthen blocks, and coating the uneven surface, whereby wearing down said coating and the protruding wood block 65 upper ends protect the edges of the earthen blocks.

In witness whereof I affix my signature.

WALTER T. MARGETTS.
